CLAIM

We claim the ornamental design for an insert for electrical sockets and electrical switches, as shown and described.

DESCRIPTION

FIG. 1 is a top front perspective view of an insert for electrical sockets and electrical switches;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in the drawings are for the purpose of illustrating portions of the article that form no part of the claim.
